UNITED STATES PATENT OFFICE.

VERN BLOMSTROM, OF DETROIT, MICHIGAN.

RAIL-TIE.

1,142,663.

Specification of Letters Patent.

Patented June 8, 1915.

Application filed October 6, 1914. Serial No. 865,365.

To all whom it may concern:

Be it known that I, VERN BLOMSTROM, a citizen of the United States, residing at Detroit, in the county of Wayne and State 5 of Michigan, have invented certain new and useful Improvements in Rail-Ties; and I do hereby declare the following to be a full, clear, and exact description of the invention, such as will enable others skilled in the art 10 to which it appertains to make and use the same.

My invention relates to new and useful improvements in rail ties and resides in the provision of a simple and inexpensive rail 15 tie that is formed of metal and will serve to support the rails in a most reliable manner so that creeping or spreading of the rails is obviated.

Another object is to provide a rail tie of 20 the character described that consists of a hollow metallic body that is rectangular and provided with open ends that are arranged to be closed by end walls or plates, said end walls being removed to permit the filling of 25 the tie with a suitable filler, if desired.

Another object is to provide a tie wherein the ends are constructed in a novel manner and so that the removable end walls therefor are removably held in proper position.

30 The above and additional objects are accomplished by such means as are illustrated in the accompanying drawings, described in the following specification and then more particularly pointed out as claimed.

35 With reference to the drawings, wherein I have illustrated the preferred embodiment of my invention as it is reduced to practice, and throughout the several views of which similar reference numbers designate corre- 40 sponding parts, Figure 1 is a top plan view of my improved tie partly broken away at one end, Fig. 2 is a fragmentary longitudinal sectional view taken on the plane of line 2-2 of Fig. 1, and Fig. 3 is a transverse 45 sectional view taken on line 3-3 of Fig. 1.

Referring to the drawings by characters of reference, 1 designates as an entirety, my

improved tie that is formed of some suitable metal and is hollow and rectangular.

The ends of the tie 1 are left open and the 50 side walls of the tie are extended and slightly reduced at their ends so as to form resilient locking tongues 2, said tie being constructed of some suitable resilient metal. The tongues 2 are slightly diverged toward 55 their outer ends relative to one another and are formed by recessing the upper and lower edges of the side walls inwardly a slight distance from the ends of the top and bottom walls, as clearly shown in Figs. 2 and 3. 60 The opposed faces of the tongues 2 at points inwardly with relation to the top and bottom walls of the tie 1 are formed with vertical grooves 3 that are designed to receive the side edges of a removable end wall or 65 closure plate 4.

As a means for securing the rail to the tie 1, I provide screw threaded rail fastening members 5 that are provided with large heads which engage upon the bases of the 70 rails. The shanks of the members 5 are inserted through the top wall of the tie 1 and have nuts 6 turned on their lower terminals.

When it is desired to fill the hollow tie body 1 with cement or any other suitable 75 filler the end walls 4 are removed by simply forcing the spring tongues 2 and 3 outwardly away from one another and the desired filler placed within the tie. To close 80 the tie at the ends the plates 4 are forced 85 into the grooves 3 in said tongues and thus are securely held in position and prevent escape of the filler within the tie.

In practice, I have found that the form 85 of my invention, illustrated in the drawings and referred to in the above description, as the preferred embodiment, is the most efficient, and practical; yet realizing that the conditions concurrent with the adoption of 90 my device will necessarily vary, I desire to emphasize the fact that various minor changes in details of construction, proportion and arrangement of parts may be re-

sorted to, when required, without sacrificing any of the advantages of my invention, as set forth.

What is claimed is:—

- 5 A rail tie consisting of a rectangular hollow metallic body portion having its ends open, the side walls of said body portion being extended beyond the top and bottom walls to form tongues, said tongues being 10 diverged toward their ends relative to one another and having their opposed faces pro-

vided with vertical notches, and removable end walls to be forced between the tongues and have their edges positioned within the notches in said tongues.

15

In testimony whereof I affix my signature in presence of two witnesses.

VERN BLOMSTROM.
